UNITED STATES PATENT OFFICE.

ANNA J. SCHRODER, OF CHARLESTON, SOUTH CAROLINA.

POWDER-PUFF.

1,168,430.

Specification of Letters Patent.

Patented Jan. 18, 1916.

Application filed June 19, 1915. Serial No. 35,157.

To all whom it may concern:

Be it known that I, ANNA J. SCHRODER, a citizen of the United States, residing at Charleston, in the county of Charleston and State of South Carolina, have invented certain new and useful Improvements in Powder-Puffs, of which the following is a specification, reference being had to the accompanying drawings.

10 This invention relates to certain improvements in powder puffs, and it is an object of the invention to provide a novel and improved device of this general character which may be employed with convenience 15 and facility in applying powder to the neck, arms and back.

Furthermore, it is an object of the invention to provide a novel and improved puff of this general character wherein the same 20 may be employed with the waste of the powder reduced to a minimum.

The invention consists in the details of construction and in the combination and arrangement of the several parts of my improved powder puff whereby certain important advantages are attained and the device is rendered simpler, less expensive and otherwise more convenient and advantageous for use, all as will be hereinafter more 30 fully set forth.

The novel features of the invention will be carefully defined in the appended claim.

In order that my invention may be the better understood, I will now proceed to 35 describe the same with reference to the accompanying drawings, wherein—

Figure 1 is a view in bottom plan of a powder puff constructed in accordance with an embodiment of my invention; Fig. 2 is a 40 longitudinal vertical sectional view of the device as herein disclosed; Fig. 3 is a transverse sectional view taken through the device as herein embodied; and Fig. 4 is a view in bottom plan, detached, of the puff proper, 45 with a portion broken away.

As herein disclosed, 1 denotes a body or the like carried by the flexible backing 2 provided with the perforations or slits 3 whereby the powder may be evenly distributed 50 through the body 1 so that the same may be applied to the person with convenience and facility.

Overlying the backing 2 is a sheet 4 of material, preferably paste-board, the marginal portions of said backing and sheet being

secured one to the other, as indicated at 5, and preferably by stitching. Initially a portion of the connection 5 is left open to afford a medium whereby the powder may be inserted within the pocket or receptacle 60 afforded by the backing 2 and the sheet 4 after which the initial opening is closed whereby the powder is entirely confined within the pocket or compartment and capable of escape only through the perforations 65 or slits 3, hereinbefore referred to.

6 denotes a head formed preferably of celluloid to which the sheet 4 is adapted to be secured, preferably by a suitable adhesive, and said head is provided with the extension 7 affording a hand grasp. The extension 7 is provided with a filler 8 of wood or the like so that sufficient rigidity and strength may be given to the extension so that the same may be readily and effectively 75 employed with the possibility of said extension becoming fractured or otherwise injured reduced to a minimum. The head 6 is also provided with a marginal flange 10 overlying the outstanding portion of the 80 strip 11 connected to the marginal portions of the backing 2 and the sheet 4 for increasing the enhansive effect, and it is to be observed that the extension 7 is of a shell formation having one face 9 separable so that 85 the filler 8 may be readily applied into operative position within the handle. In addition to affording means for mounting the head 6, the strip 11 serves to reinforce the marginal portion of the backing 2 and the 90 sheet 4.

It is thought to be self-evident that by mounting the body 1 upon the head 6 provided with the extension or handle 7 that powder may be conveniently applied to various 95 parts of the person, especially the neck, arms and back.

From the foregoing description, it is thought to be obvious that a powder puff constructed in accordance with my invention is of an extremely simple and comparatively inexpensive nature and is particularly well adapted for use by reason of the convenience and facility with which it may be assembled, and it will also be obvious that 105 my invention is susceptible of some change and modification without material departure from the scope of the appended claim and for this reason I do not wish to be understood as limiting myself to the precise 110

arrangement and formation of the several parts herein shown in carrying out my invention in practice.

I claim:

- 5 A powder puff comprising a fleecy body provided with a perforate backing and a sheet of material overlying said backing, the marginal portions of said backing and sheet being secured one to the other to afford
- 10 a pocket, a head to which the outer face of the sheet is secured, and a strip secured to

the connected marginal portions of the backing and sheet and provided with an outstanding portion, the head being provided with a marginal flange overlying the outstanding portion of the strip. 15

In testimony whereof I hereunto affix my signature in the presence of two witnesses.

ANNA J. SCHRÖDER.

Witnesses:

J. R. KELLY,
HUGO JAHNZ.
